Joshua P. Ross
HIS ATTORNEY

UNITED STATES PATENT OFFICE

HARRY STEIN, OF PHILADELPHIA, PENNSYLVANIA

EXTENSIBLE SLEEVE

Application filed June 27, 1931. Serial No. 547,223.

This invention relates to extensible sleeves, and has for an object to provide an improved structure whereby the initial length of the sleeve may be increased as the requirements of the wearer dictates.

A further object of the invention is to provide a sleeve having a cuff thereon, with means obscured by the cuff, whereby certain stitches may be ripped for the purpose of 10 lengthening the sleeve without changing the appearance of the sleeve and cuff.

A further object of the invention is to provide a sleeve having a folded back part, stitched in a plurality of stitches, with a cuff 15 folded over the stitching to at all times obscure the stitching, permitting the stitching to be ripped without changing the relative appearance of the sleeve and cuff.

The invention, therefore, comprises a sleeve 20 folded back upon itself, with the back folded part having a cuff secured thereto, a part of the cuff being also stitched to the back folded part in a plurality of rows of stitching which may be ripped for the purpose of extending 25 the cuff further along upon the sleeve.

The invention is directed to other objects, and possesses other features of novelty and advantage, some of which, together with the foregoing, will be hereinafter more fully set 30 forth.

In the drawings:

Figure 1 is a view of the improved sleeve, shown as an exterior view, with parts broken away, and

35 Figure 2 is a view of the sleeve shown from the interior, a part being broken away and a part shown in section.

Like characters of reference indicate corresponding parts throughout the several views.

40 The improved extensible sleeve, which forms the subject matter of this application, comprises a sleeve part 10, of substantially the usual and ordinary type, folded back at 11 to form the lap 12. To the then upper edge 45 13, of this lap 12, the inner part of the cuff 14 is secured by the stitches 15, and such auxiliary stitches as may be found desirable. The cuff also includes a lining part 16 which is stitched to the lap 12 in a plurality of rows 50 of stitchings 17, 18 and 19. The exterior part

of the cuff 20 is secured to the lower edge of the interior part by the stitching 21, and any auxiliary stitching found desirable. It will be noted especially by reference to Figure 2, that from the extreme row of stitching, shown 55 as 17 in that figure, the cuff folds back over both the interior and exterior of the sleeve, and that the rows of stitchings 17, 18 and 19 are completely obscured thereby. A button-hole 22 is provided in the cuff which should be below the fold 11, and a button 23 when used, will be similarly located.

The sleeve and cuff thus assembled, will have every appearance of an ordinary sleeve and cuff. In case the sleeve, as marketed, is not of such length as required by the user, then one or more of the rows of stitchings 17, 18 or 19 are ripped. These rows of stitchings 17, 18 and 19 may be spaced at any desired interval, and the showing in the drawings is only illustrative. Assuming merely for the purpose of illustration, that the stitchings are spaced one-half inch apart, then by ripping the row of stitching 17, the cuff will be moved downwardly upon the 70 sleeve so that the fold 11 will now be at the row of stitching 18, and the overall sleeve length will be increased one inch. By ripping the stitching 18 also, the cuff may be moved one inch further so that the fold 75 will be at the stitching 19, and the sleeve will be lengthened two inches. By ripping the stitching 19, the sleeve will then connect with the upper edge of the interior 14 of the cuff and the sleeve will be lengthened 80 three inches.

It should be noted, that in either of the positions where a fold of the fabric, determined by a row of stitching also determines the length of the sleeve, these rows of stitchings are entirely obscured by the folded back portion of the cuff, and the appearance of the sleeve and cuff is not different from that of an ordinary sleeve and cuff. When all of the stitching has been removed, the 90 cuff will still appear to be attached to the sleeve in the usual and ordinary manner.

By the use of this device, sleeves of a standard short length may be marketed with the assurance that users requiring longer sleeves 95 100

will be accommodated by the same garment by merely lengthening the sleeve in the manner outlined.

The drawing indicates a shirt sleeve, and 5 the present indications are that this type of sleeve will define the greatest utility of the invention, but it is to be understood that the sleeve and cuff here disclosed is not confined in its utility to shirts, and may be applied 10 to other garments as may be found desirable.

Of course, the extensible sleeve, herein described, may be modified and changed without departing from the invention herein set forth and hereinafter claimed.

15 The invention is hereby claimed as follows:

1. The combination of a sleeve and a folded cuff, the sleeve being folded back upon itself and the fold inclosed within the fold 20 of the cuff with the folded back section stitched to the inner face of the cuff by a plurality of rows of stitches.

2. The combination of a sleeve and a folded cuff, the sleeve being folded back upon 25 itself and the fold inclosed within the fold of the cuff with the folded back section only stitched to the inner face of the cuff by a plurality of rows of stitches.

3. The combination of a sleeve and a folded cuff, the sleeve being folded back upon 30 itself and the fold inclosed within the fold of the cuff with the folded back section stitched to the inner face of the cuff by a plurality of rows of stitches substantially 35 parallel with the fold of the cuff.

4. The combination of a sleeve and a folded cuff, the sleeve being folded back upon itself and the fold inclosed within the fold 40 of the cuff with the folded back section stitched to the inner face of the cuff by a plurality of rows of stitches, said stitches being concealed upon one side by the sleeve and upon the other side by the cuff.

5. The combination of a sleeve and a folded cuff, the sleeve being folded back upon 45 itself and the fold inclosed within the fold of the cuff with the folded back section only stitched to the inner face of the cuff by a plurality of rows of stitches substantially 50 parallel with the fold of the cuff, said stitches being concealed upon one side by the sleeve and upon the other side by the cuff.

In testimony whereof I have signed my name to this specification.

65 HARRY STEIN.
